UNITED STATES PATENT OFFICE.

FREDERICK B. MAGILL, OF ST. MARYS, OHIO.

GUN-SIGHT.

1,313,549.

Specification of Letters Patent.

Patented Aug. 19, 1919.

Application filed April 3, 1919. Serial No. 287,112.

To all whom it may concern:

Be it known that I, FREDERICK B. MAGILL, a citizen of the United States, residing at St. Marys, in the county of Auglaize and 5 State of Ohio, have invented certain new and useful Improvements in Gun-Sights, of which the following is a specification.

The invention provides a device for the use of sportsmen to be applied to the muzzle 10 of a shot gun or rifle to enable a bird on the wing to be properly and accurately sighted to insure a hit being made when the gun is fired, the device being of such construction as to obviate calculation on the 15 part of the gunner and adapted to be readily attached to or disconnected from the gun barrel.

The drawing illustrates a preferred embodiment of the invention. However, it is to 20 be understood that in adapting the same to meet different conditions, various changes in the form, proportion, and minor details of construction may be resorted to without departing from the nature of the invention 25 as claimed hereinafter.

Referring to the drawing hereto attached, Figure 1 is a plan view of a gun sight showing the same in position.

Fig. 2 is a rear view, the barrel of the gun 30 being in cross section.

Fig. 3 is a cross section of the sight on the line 3-3 of Fig. 2 showing a portion of the gun barrel in full lines.

Fig. 4 is a sectional detail on the line 35 4-4 of Fig. 2, the muzzle portion of the gun barrel being shown.

Fig. 5 is a detail perspective view of the device.

Fig. 6 is a plan view of the blank from 40 which the sight is formed.

Corresponding and like parts are referred to in the following description and indicated in the several views of the drawing by like reference characters.

45 The numeral 1 designates the muzzle portion of a shot gun or rifle such as used by sportsmen when hunting. The numeral 2 designates the front sight such as generally provided near the muzzle of the gun. These 50 parts are of well known construction and are illustrated to demonstrate the application of the invention.

The device comprises a base 3 and wings 4. The base 3 is relatively narrow and long 55 and is provided at opposite ends with sights 5 which are preferably partly cut from the

base and pressed upwardly therefrom, as indicated most clearly in the several views. The wings 4 extend in parallel relation and constitute a part of the base 3. The wings 60 4 are widened at a central point and taper toward opposite ends. Openings 6 are formed in the central widened portions of the wings 4 and are of a size to snugly receive the muzzle of the gun barrel 1. A 65 plurality of teeth 7 are in line with the openings 6 and extend laterally from the wings to frictionally engage the barrel 1 and retain the device in position against any possible movement. The teeth 7 form a part 70 of the device and possess a spring action to engage the gun barrel with sufficient friction and a gripping action to hold the sight in position under ordinary conditions. Two fingers 8 are provided at the rear side of the 75 base 3 and extend transversely thereof and are formed near their inner ends with notches 9 to receive the sight 2. The fingers 8 are centrally disposed and are formed by cutting away portions of the base 3 as indicated most clearly in Figs. 1 and 6. The fingers 8 are adapted to spring apart when placing the device in position or removing it from the gun barrel.

As indicated most clearly in Fig. 6 the device is formed from a sheet metal blank cut into the form substantially as indicated and having side portions bent on the dotted lines to form the wings 4 and the parts 5 and 7 bent to form the sights 5 and teeth or gripping elements 7. The sights 5 are disposed at such distance from a central point as to insure proper and accurate sight being obtained on a moving object such as a bird on the wing, thereby enabling the mark to be 95 hit without requiring the sportsmen to make any allowance or calculation. When the device is in position the muzzle of the gun barrel 1 passes through the openings 6 of the wings 4 and the teeth 7 bear against 100 the side of the gun barrel and retain the device in position. The sight 2 at the muzzle of the gun passes between the spring fingers 8 and is received in the notches 9, thereby materially assisting in holding the 105 device in position and at the same time insuring the base occupying a horizontal position so that both sights 5 may be level when the gun is aimed. The fingers 8 in conjunction with the usual sight 2 insure 110 proper positioning of the device when slipped upon the muzzle of the gun barrel.

When required the device may be detached from the gun and conveniently carried in the game bag or other place.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. A gun sight, comprising an elongated base having sights on opposite end portions and provided at a central point with parallel spring fingers disposed at a right angle to the length of the base and adapted to engage a side of the gun barrel and grip the ordinary gun sight between them.

2. A gun sight, comprising a base having sights at opposite ends and provided with a wing in which is formed an opening to receive the barrel of the gun, said wing having spring elements in line with the opening to engage the gun barrel frictionally and retain the sight in place thereon.

3. A gun sight, comprising a base provided at opposite ends with sights and having spaced elements intermediate of its ends to receive the ordinary gun sight and pro-

vided with a depending wing in which is formed an opening to receive the gun barrel and having spring elements in line with the opening to engage the barrel of the gun and retain the device thereon.

4. A gun sight, comprising a base having end portions partly cut therefrom and bent to form opposite sights and having a central portion cutaway to provide spring fingers for engaging the ordinary gun sight.

5. A gun sight, comprising a base having side wings formed with central openings to receive the gun barrel and having sights at opposite ends and centrally disposed spring fingers to receive the ordinary gun sight.

6. A gun sight, consisting of a single blank of sheet metal, comprising an oblong base and side wings, the oblong base having end portions partly cut therefrom and bent outwardly to form sights and having a central portion cutaway to provide spring fingers which have their opposing portions formed with registering notches, the side wings having openings to receive the gun barrel and having teeth in line with the openings to engage the gun barrel and retain the device in position thereon.

In testimony whereof I affix my signature in presence of two witnesses.

FREDERICK B. MAGILL.
